JOHN M. GLASER, OF BUFFALO, NEW YORK, ASSIGNOR TO U. S. NAME COMPANY, OF BUFFALO, NEW YORK.

BUCKLE AND METHOD OF MAKING SAME.

Application filed December 29, 1926. Serial No. 157,802.

This invention relates to improvements in buckles of the kind commonly used in connection with straps or belts, and more particularly this invention relates to buckles of this kind in which the frame or body portion is made of a wire or rod bent or formed into the desired shape, and also to methods of making such buckles.

The objects of this invention are to provide a buckle of this kind in which the body portion of the buckle is provided with an offset bearing or seat for the tongue of the buckle, which assures a smooth operation of the tongue of the buckle and also prevents the tongue from moving sidewise on the body portion of the buckle; also to devise an improved process of making buckles of this kind; also to improve constructions and methods of this kind in other respects hereinafter specified.

In the accompanying drawings,

Fig. 1 is a top plan view of the mechanism for forming the body portion of the buckle embodying my invention in accordance with my improved process.

Fig. 2 is a sectional plan view thereof on line 2-2, Fig. 3.

Fig. 3 is a sectional plan view thereof on line 3-3, Fig. 2.

Fig. 4 is a face view of a buckle embodying my invention, the portion of the tongue of the buckle which bears on the body portion being shown in section.

Fig. 5 is a sectional view of the body portion of the buckle on line 5-5, Fig. 6.

Fig. 6 is a face view of the body portion of the buckle before the tongue is attached thereto.

Fig. 7 is a sectional view of the completed buckle on line 7-7, Fig. 4.

The frame or body portion of the buckle as shown in Figs. 4 to 7 is made of wire and is in the form of a substantially rectangular loop having an end 5 to which the tongue 6 of the buckle may be secured, and which is generally fastened to one end of a strap or belt. The wire or rod is bent to form the sides 7 and 8 of the body portion of the buckle and the other end 9 of the body portion is preferably formed by bending the two ends of the wire loop toward each other and this joint is preferably welded as shown at 10. The end 9 of the body portion is preferably provided with the usual sheet metal

sleeve 11 rotatably mounted on this portion 55 of the body portion of the buckle and with which a strap or belt may engage and against which the free end of the tongue 6 rests. The other end of the tongue is preferably bent in the usual manner about the middle portion 60 of the end 5 of the frame member so that the tongue can swing about this portion of the frame of the buckle. All of these parts are of themselves old in connection with buckles.

It will be obvious that it is desirable that 65 the tongue 6 should remain centrally disposed on the body portion of the buckle and it is also desirable that this tongue should operate freely without binding on the body portion of the buckle during the swinging 70 of the tongue, and for this purpose in the particular construction shown, an offset bearing 12 is formed on the end portion 5 of the frame or body portion of the buckle. This bearing portion 12 of the buckle is cylindrical 75 in form so that the loop portion 14 of the tongue 6 can swing freely about the bearing, and the length of this cylindrical bearing portion 12 is slightly in excess of the width of the loop portion 14 of the tongue 80 and terminates at the outer end of the buckle in crescent shaped shoulders 15 which serve to limit the sidewise movement of the tongue 85 on the body portion of the buckle. The other side of the bearing portion projects slightly toward the inside of the looped body portion of the buckle.

The body portion of the buckle is preferably formed from a straight piece of a suitable wire or rod α , Fig. 1, by means of dies 90 which bend the body portion around a mandrel, and the dies and mandrel are provided with parts which at the same time form the offset bearing portion 12, as shown in Figs. 1 to 3, in which A represents the mandrel 95 having a recess a therein into which the inwardly extending portion 16 of the bearing part 12 is forced during the formation of the body portion of the buckle. B represents a die having projecting portions or arms b 100 and b' which bend the sides 9 and 10 of the buckle around the sides of the mandrel. The die B has a forwardly projecting portion b^2 which is adapted to form the outer face of the bearing portion 12 and at the same time 105 to form the shoulders 15 by pressing the bearing portion out of alignment with the end member 5 of the body portion of the

buckle. The portion or face of this projection b^2 which engages the end portion 5 of the body of the buckle to form the bearing portion 12 is rounded in such a manner as 5 to retain the cylindrical surface of the portion of the body portion engaged thereby, and since the opposite face 16 of the bearing portion 12 is not in any way deformed, but is simply pressed into the groove a , this portion of the bearing retains the original cylindrical form of the wire or rod α . C and D represent laterally movable dies which bend the ends of the wire, from which the body portion of the buckle is made, toward each 10 other to form the end 9 of the body portion of the buckle.

My improved process consists of forming a wire or rod by means of dies about a mandrel and at the same time forming on one 20 end of the body portion of the buckle an offset bearing portion of cylindrical shape to form a proper bearing for the loop portion 14 of the tongue of the buckle which surrounds the bearing portion 12. This formation of the offset bearing portion is effected by pressing a part of one end of the body portion of the buckle by means of a projection on the die which forms the sides of the body portion into a recess in the mandrel. The 25 projection on the die is so formed as not to deform the cylindrical surface of the material from which the buckle body is made, and the recess a is of sufficient depth so that the portion 16 of the bearing 12 is not deformed 30 by contact therewith, so that a cylindrical offset bearing portion results on which the tongue 6 of the buckle can swing freely. By offsetting the bearing portion 12 as described the shoulders 15 are also formed, which limit 35 the lateral movement of the tongue on the body of the buckle. By means of this process the formation of the offset bearing portion 12 and the shoulders 15 is effected in one operation with the forming of the body of the 40 buckle, thereby effecting a considerable saving in the cost of producing buckles of this kind, and also insuring a cylindrical bearing terminating in abrupt shoulders which prevent binding of the tongue while swinging 45 about its pivoted connection with the end of the buckle. When the wire or rod α is bent about the mandrel by the arms b and b' of the die B, the portion 5 of the body of the buckle tends to bend away from the adjacent 50 face of the mandrel and in accordance with my improved process the straightening or bending of this part of the body is effected simultaneously with the formation of the offset bearing portion 12. After the body of 55 the buckle with the offset bearing portion is formed, the tongue can be pivotally mounted on the buckle by bending the loop portion 14 thereof around the offset bearing portion.

On buckles of this kind as heretofore made 60 it is customary to form the bearing for the

tongue of the buckle in alinement with the side of the body portion of the buckle on which the tongue is pivoted, and then deforming portions of this side of the buckle at opposite sides of the loop of the tongue to 70 prevent sidewise movement of the tongue thereon. These deformations on the side of the body portion of the buckle can, however, not be made with sharp shoulders such as the stop shoulders 15 shown in the drawings, 75 and consequently the tongues of buckles heretofore made have a tendency to bind upon the retaining deformations on the body portion of the buckles so that it is at times very difficult to move the tongue of the buckle 80 either into its open or closed position. By means of my improved buckle there is no tendency of the tongue of the buckle to bind, and the tongue can consequently readily be moved into either its open or closed position. 85

I claim as my invention:

1. A buckle having a body portion formed of a rod, and a tongue pivoted on one end of the body portion, said end of the body portion having a bearing for said tongue formed 90 therein intermediate of the ends of said rod and offset with reference to said end of said body portion.

2. A buckle having a body portion formed of a rod bent to form sides and ends and having a tongue pivoted on one end of said body portion and having the ends of the rod meeting at the other end of said body portion, said body portion having said end thereof on which said tongue is pivoted formed to produce a bearing offset with reference to said end of said body portion and terminating in shoulders which limit the lateral movement of 100 said tongue on said body portion.

3. A buckle having a body portion formed of a rod bent to form the body portion and having its ends meeting at one end of said body portion, and a tongue pivoted on the other end of the body portion, the middle portion of said last mentioned end of said body portion being offset with reference to other portions of said last mentioned end and being substantially circular in cross section to form a bearing for said tongue, said offset bearing portion forming shoulders with said end at opposite sides of said bearing portion, which shoulders limit the lateral movement of said tongue on said end of said body portion. 110 115

4. A buckle having a body portion formed of a rod of substantially circular cross section bent to form sides and ends, one end of said body portion having a part intermediate of said sides pressed out of alinement with other parts of said end and forming shoulders with adjacent portions of said end to form an offset bearing which is of substantially circular cross section throughout its length, said bearing being arranged intermediate of the ends 120 125 of the rod, and a tongue having one end there- 130

of looped around said offset bearing portion and confined against lateral movements on said end of the body of the buckle by said shoulders.

5. The process of forming the body portion of a buckle consisting of bending a rod to form sides and ends of said body portion and at the same time pressing a portion of said rod intermediate of the ends thereof out of 10 alinement with adjacent portions to form a cylindrical offset bearing portion of substantially circular cross section terminating in stop shoulders and welding the ends of said rod together at the side of said buckle opposite to that in which said bearing portion is formed.

6. The process of forming a buckle consisting of bending a rod of substantially circular cross section to form sides and ends of the 20 body portion of the buckle, deforming a part of one end of said body portion intermediate of the sides thereof and between the ends of said rod to form stop shoulders, securing a tongue of the buckle to said end by bending 25 a portion of said tongue around said bearing

end between said stop shoulders and welding the ends of said rod together at the side of said buckle opposite to that to which said tongue is secured.

7. A buckle having a body portion formed by looping a rod and welding the ends of said rod together, a tongue pivoted on said body portion, the part of said body on which said tongue is pivoted being offset with reference to adjacent parts of said body portion to hold 30 said tongue against moving lengthwise of said body portion, and being located at a distance from said welded ends.

8. A buckle having a body portion formed by looping a rod and welding the ends of said rod together, a tongue pivoted on said body portion, the part of said body on which said tongue is pivoted being deformed to form shoulders at opposite sides of said tongue to hold 35 said tongue against movement lengthwise of said part of said body portion, and being located at a distance from said welded ends.

JOHN M. GLASER.
